TIN-PLATE FLOWING APPARATUS

Milton P. Vore, Catonsville, Md., assignor to Westinghouse Electric Corporation, East Pittsburgh, Pa., a corporation of Pennsylvania

Application November 11, 1942, Serial No. 465,270

3 Claims. (Cl. 219—13)

My invention relates to high-power radio-frequency inductive heating apparatus, and it has particular relation to apparatus of this kind, having so much power that it is necessary, or desirable, for one reason or another, to subdivide the energy into a number of separate oscillation-generators, each feeding power to a separate coil-section of the induction heating coil.

Although my invention, in its broadest aspects, is not limited to any particular field of application, the most important present field of application for my invention is in connection with the tinplate-flowing apparatus which is described and claimed in an application of Glenn E. Stoltz and Robert E. Baker, Serial No. 464,040, filed October 31, 1942, and assigned to the Westinghouse Electric & Manufacturing Company. In this tinplate-flowing application of my invention, a miles-long strip of steel, or other magnetizable metal, is caused to run, at a very high rate of speed, through a tinning "line," in which various operations are successively performed on the strip, including electrolytically tinplating it on both sides, quickly heating it to a temperature of 452° F., or slightly thereafter, for the purpose of melting the tinplate and causing it to flow evenly and glossily over the surface of the steel to enhance its corrosion-resistant properties, as well as improving its appearance, subsequently quenching the strip, and performing various additional operations thereon, having nothing to do with the present invention, except that it is necessary to gauge the rate of heat-input into the strip to correspond to the large poundage of material which has to be heated per minute, preferably within as short a strip-length as is practically possible.

The most satisfactory method of heating such a fast-moving strip, and practically the only method of controllably introducing the necessary quantity of heat within an acceptably short length of the fast-moving strip, is the inductive heating method, in which the strip is passed axially through an inductive heating-coil which is supplied with a large amount of power from a high-capacity oscillator-tube generator-means. In a typical tinplate-flowing application of my invention, the inductive heating-coil receives many times as much energy as is used by the largest radio broadcasting station in the United States. With such large energy-input into the inductive heating-coil, the problem of generating that much energy, and of getting it into the heating-coil, becomes of paramount importance.

The object of my invention is to provide a plu-

rality of coil-sections, for the inductive heating-coil, and a plurality of separate, complete, oscillation-generators, one for each coil-portion. The plurality of coil-portions are axially spaced, so as to be operative upon the same work to be heated, and preferably the axial space is made sufficient so that there is not a very close coupling between adjacent coil-portions. Preferably, also, the oscillation-generators are tuned to slightly different frequencies, so as still further to reduce the likelihood of coupling, or energy-feedback, between adjacent coil-portions. The reduced coupling between adjacent heating-coils, and hence between the output-circuits of two oscillators that would normally operate at slightly different frequencies, prevents these oscillators from operating in step at some compromise frequency different from the natural frequency of either one separately, as they would do if their output-circuits were strongly coupled. The result of such forced oscillation, at a compromise frequency, would be that the load on the anode of each oscillator-tube would have a reactive component which would cause excessive anode-loss and heat-generation under such circumstances of strong coupling, thus sharply reducing the amount of energy which could be handled by each tube. The reduced coupling between out-of-tune oscillators prevents this excessive heat-generation at the anodes, and it also overcomes a tendency for one of the oscillators to "hog" the load because of its feedback-coupling.

With the foregoing and other objects in view, my invention consists in the apparatus, combinations, circuits, systems, parts and methods hereinafter described and claimed, and illustrated in the accompanying drawing, the single figure of which is a simplified diagrammatic view of circuits and apparatus illustrative of my invention.

I have illustrated my invention as being applied to the rapid inductive heating of a rapidly moving tinplated steel strip 1, which generally has a gauge of between 0.008 and 0.011 inch, with a width of the order of 28 to 36 inches, more or less, and which is moving, in the direction of its length, at a speed which may be of the order of a thousand feet per minute, more or less. This strip 1 passes axially downwardly through an inductive heating coil 2, comprising a plurality of axially spaced coil-portions or sections 3, 4, 5, 6, 7 and 8. Each coil-portion comprises a plurality of turns of a suitably cooled conductor, wound in a single layer, and having flat coil-sides 10 which are spaced from the oppo-

site flat surfaces of the strip 1 which is being heated.

The coil-portions 3, 4, 5, 6, 7 and 8 are each energized by means of a separate oscillation-generator 13, 14, 15, 16, 17 and 18 respectively. Each oscillation-generator comprises one or more oscillator-tubes 19, which are illustrated, in their simplest form, as having a cathode 20, an anode 21, and a grid or other control-means 22. The anode 21 is connected, through a blocking capacitor 23, to a tank-circuit which comprises a tank-capacitor 24, a tank-inductance 25, and the coil-section, such as the coil-portion 3, which is supplied with energy by that particular oscillation-generator. The connection between the plate-circuit blocking-capacitor 23 and the tank-circuit is illustrated as being made at the junction-point 26 between the tank-capacitor 24 and the tank-inductance 25, while the other terminal of the tank-capacitor 24 is illustrated as being grounded, at 27. The cathode-circuit of the oscillator-tube is also grounded, as indicated at 28.

Feedback-energy is illustrated as being obtained from the tank-circuit, as by means of a secondary winding 29 which is inductively coupled to the tank-inductance 25, and which energizes the grid 22 of the oscillator-tube through a grid-leak resistance 31 which is shunted by a grid-capacitor 32.

Each of the oscillation-generators 13, 14, 15, 16, 17 and 18 is supplied with direct-current power by having its anode 21 connected through a choke-coil 34, to the positive bus 35 of the plate-voltage supply. Thus the power-supply bus 35 and the grounded cathode-connections 28 constitute the power-supply buses (+) and (-) for all of the oscillation-generators 13, 14, 15, 16, 17 and 18.

The power-supply back of the oscillator-buses (+) and (-) is illustrated as being derived from a three-phase line 41, which supplies power, through a circuit breaker 42 and an induction regulator 43, to the primary winding 44 of a step-up rectifier-transformer 45, which is illustrated as having two star-connected secondary windings 46 and 47, the star-points of which are joined by an interphase-transformer 48, the midpoint of which is grounded so as to constitute the negative bus (-) of the oscillator power-source. The phase-terminals of the secondary windings 46 and 47 are connected, through a plurality of rectifiers 49, to the conductor 35 which constitutes the positive bus (+). The induction regulator 43 is capable of being rapidly adjusted so as to obtain preferably 100% voltage-regulation, so that the temperature to which the strip 1 is heated may be accurately controlled, as explained in the Stoitz-Baker application.

In operation, it will be observed that each of the oscillation-generators 13, 14, 15, 16, 17 and 18 supplies high-frequency power to its own coil-portion 3, 4, 5, 6, 7 and 8 as the case may be. Because of the special exigencies of the use to which the oscillation-frequency power is being put, it is practically necessary to operate each oscillation-generator at an abnormally high Q, or high ratio of wattless power, which is stored in the tank-circuit, to the actual power which is delivered to the work to be heated. This is because it is necessary to be able to start up the apparatus, of course; and this starting must necessarily be done when the steel strip is cold, at which time the generator may have a Q of the order of 10, whereas, when the strip is hot, the Q may be as high as 30.

Because of the high Q of the generator, it is

impossible to utilize two loosely coupled tuned circuits, with the air-coil couplings such as are commonly utilized in high-frequency circuits, because a very slight relative detuning of the two circuits, one with respect to the other, at such a high Q, will make it practically impossible to transfer any material amount of power from one circuit to the other. It is necessary, therefore, to include the inductive heating-coil in series-circuit relation as an effective part of the tank-circuit of its own oscillator, for controlling the oscillator-frequency, so that, when the inductance of the coil changes in accordance with the condition of the work, as in the change which is involved between initially starting the apparatus when the strip is cold, and thereafter operating the apparatus when the strip is hot, the frequency of the oscillation-generator will vary with the change in the effective reactance of the heating-coil; this frequency-change being small, but, nevertheless, important, and in fact the difference between being able to get the power into the strip and not being able to do so, in many cases.

Thus, it will be noted that each of the coil-portions of the inductive heating-coil 2 is serially included as a part of the inductance of the tank-circuit of its own oscillation-generator, so that any change in the heating-coil inductance will be reflected in a corresponding change in the tuning of the generator. In this manner, I am able to pass from cold-strip operating-conditions to hot-strip operating-conditions, and I am also able to handle strips which are not always of the same uniform gauge or thickness.

The inclusion of the heating-coil 2 as a series portion of the tank-circuit has the advantage of being the simplest scheme and also having more efficient energy-transfer than is feasible with any sort of link-coupling scheme, regardless of the Q of the tank-circuit.

The several tank-circuits of the respective oscillation-generators 13, 14, 15, 16, 17 and 18 are not all tuned to each other, which is another way of saying that they will not all be of the same frequency. Thus, if the general operating-frequency is of the order of 200 kilocycles per second, the individual frequencies of the separate oscillation-generators may vary, for example, between 190 kilocycles and 210 kilocycles, more or less. The successive coil-portions 3, 4, 5, 6, 7 and 8 are physically separated from each other, in an axial direction, along the length of the strip 1, by a distance which may be of the order of a foot, or other distance such that the axially flowing fluxes in the successive coils have become considerably attenuated before successive coil-sections are reached, thus considerably reducing the amount of coupling between the several coil-sections. Thus, none of the oscillation-generators is materially affected by the loosely coupled circuits of slightly different frequencies, which are loosely coupled by the several axially spaced heating-coils 3 to 8. This reduced coupling between the heating-coils prevents the excessive anode-losses that would otherwise be encountered in the tubes, and it also avoids the tendency for one oscillation-generator to take more than its share of the total load, as previously explained.

While I have illustrated my invention in a single illustrative form of invention, which has been shown in substantially its simplest, idealized form, I wish it to be understood that the usual features and safeguards, such as are commonly understood in the art, will be employed, 75 without departing from my invention, and in

fact as a part of any actual embodiment of my invention. For example, all of the conductors which carry radio-frequency power should be suitably cooled, as is well understood in the art, usually by means of water-cooling (not shown). I wish it to be understood, also, that various changes, by way of substitutions, additions, and omissions, may be made, without departing from the essential features of my invention. I desire, therefrom, that the appended claims shall be accorded the broadest construction consistent with their language and the prior art.

I claim as my invention:

1. Induction-heating apparatus for inductively heating an elongated member which is continuously moving in the direction of its length, said induction-heating apparatus comprising a plurality of spaced, coaxial induction-heating coils, following one another along a line adapted to correspond to the length of the elongated member, the magnetic coupling between successive induction-heating coils being weak, a separate oscillation-generator means for separately energizing each induction-heating coil with oscillation-frequency energy, each oscillation-generator means having a tank-circuit effectively serially including its own induction-heating coil, the inductance of each induction-heating coil being variable in accordance with the condition or nature of the member being heated, and hence the frequency of each oscillation-generator tank-circuit being correspondingly variable, the ratio Q ,

between the wattless power stored in each tank-circuit and the actual power delivered by its induction-heating coil to the member being heated, being variable in response to the nature or condition of the member being heated, said ratio Q being greater than 10 under certain operating conditions, whereby the several oscillation-generator means are not materially affected by loosely coupled circuits of slightly different frequencies, and feedback-means from each tank-circuit for keeping its oscillation-generator means oscillating, the tank-circuits of the several oscillation-generator means being tuned to a plurality of different frequencies, whereby the several oscillation-generator means are operable, each at its own frequency, substantially independently of the frequency of the other oscillation-generator means, thus avoiding excessive internal overheating as a result of the reactive components of the currents in the several oscillation-generator means, and also avoiding any excessive tendency for any one oscillation-generator means to "hog" the load because of its feed-back coupling.

2. The invention as defined in claim 1, characterized by the several oscillation-generator means having all about the same frequency, with sufficient differences to prevent substantial coupling through adjacent induction-heating coils.

3. The invention as defined in claim 1, in combination with a common, variable-voltage, direct-current supply-means for energizing all of the oscillation-generator means.

MILTON P. VORE.
